ELECTRIC PLUG

Woodrow A. Bowman, St. Joseph, Mich., assignor to Welco Electric Corporation, Berrien Springs, Mich., a corporation of Michigan

Filed Jan. 18, 1965, Ser. No. 83,476

Term of patent 3½ years

(Cl. D26—1)

FIG. 1

FIG. 4

FIG. 2

FIG. 5

FIG. 3

FIGURE 1 is a side elevational view of an electric plug, showing my new design;

FIGURE 2 is an edge elevational view thereof.

FIGURE 3 is an elevational view of the side opposite that shown in FIGURE 1;

FIGURE 4 is a left end elevational view thereof; and

FIGURE 5 is an elevational view of the end opposite that shown in FIGURE 4.

I claim:

The ornamental design for an electric plug, substantially as shown.
